KNIFE

Roger L. Kelly, Arlington Heights, Ill., assignor to American Home Products Corporation, New York, N.Y., a corporation of Delaware

Filed Nov. 22, 1967, Ser. No. 9,503

Term of patent 14 years

U.S. Cl. D95—3

Int. Cl. D7—03

FIG. 1 is a side elevational view of a knife showing my new design.

FIG. 2 is a top plan view thereof.

FIG. 3 is an enlarged section taken along line 3—3 of FIG. 1.

FIG. 4 is an enlarged section taken along line 4—4 of FIG. 1.

FIG. 5 is an enlarged view of an area of the blade within boundaries of circular lines in FIG. 1 to illustrate contrasting surface ornamentation of the blade throughout the length of its cutting portion in relation to the shank of said blade.

The dominant features of my design reside in the portion shown in full lines and particularly in the configuration of the inwardly cut heel at the shank of a blade which is of otherwise conventional configuration.

I claim:

The ornamental design for a knife, substantially as shown and described.
